(57) **CLAIM**

The ornamental design for a multi-purpose transceiver for locating objects, as shown and described.

DESCRIPTION

FIG. 1 is a front elevation view of a multi-purpose transceiver for locating objects showing my new design;

FIG. 2 is a rear elevation view thereof;

FIG. 3 is a side elevational view thereof;

FIG. 4 is a top plan view thereof; and,

FIG. 5 is a bottom plan view thereof.

The broken lines shown in the drawings form no part of the claimed design.
